5 Claims. (Cl. 137—622)

This invention relates to control valves for hydraulic presses of the direct-hydraulic type in which pressure liquid to actuate the press is supplied directly by pumps. In particular this invention relates to upwardly acting hydraulic presses in which the pressing stroke is in an upward direction.

One object of this invention is to provide an improved construction whereby the control valve is mounted upon a combined prefilling and exhaust valve and is adapted to actuate the said exhaust valve to effect the return stroke of the press ram, the said combined valve being equally suitable for employment with a hydraulic press having one press ram or having a multiplicity of press rams.

Broadly the present invention consists of a combined control prefilling and exhaust valve for use with an hydraulic press and in combination with an automatic admission valve wherein with the control valve in the neutral position both the pump and the approach cylinders of the press are free to exhaust by way of the control valve, with the control valve in the return stroke position the exhaust valve opens to permit the one or more press rams to exhaust concurrently with the pump and the approach cylinders which are still free to exhaust through the control valve and with the control valve in the pressing position the exhaust valve is free to close and delivery from the pump is diverted to the approach cylinders until a pressure rise in such cylinders effects operation of the automatic admission valve when the pump is permitted to deliver to the one or more press cylinders as well as the approach cylinders.

One embodiment of this invention consists of a manually operated single acting control valve mounted upon a combined prefilling and exhaust valve, the axis of the control valve spindle being co-axial with the axis of the said combined valve, the spindle of the control valve being connected to the combined valve in such a way that, when it is moved to the "return" position, it actuates the exhaust valve causing the said valve to open so as to permit pressure liquid from the press cylinder to pass back to the pump supply tank and so arranged that, when the control valve spindle is moved in the opposite direction, towards the "pressing" position, the said exhaust valve is permitted to close. The combined prefilling and exhaust valve comprises three mushroom type valves mounted concentrically one within the other. The largest mushroom type valve functions as a prefilling valve and is seated in the main valve casing on which the control valve is mounted with the axis of the valve spindle co-axial with the axis of the prefilling valve. The prefilling valve is held closed by a spring or springs acting in opposition to the pressure of liquid from the supply tank which tends to open the valve. The exhaust valve is seated within the prefilling valve head and is held closed by a spring. The exhaust valve head is enlarged to form a piston which is enclosed by a cylindrical bore within the prefilling valve head and it is so arranged that the exhaust valve head functions as a piston within the bore in the prefilling valve head which functions as the associated cylinder.

2

The annular area of the piston surrounding the exhaust valve seat is subject to the pressure within the press cylinder; the full area of the piston within its associated cylinder is also subject to the pressure within the press cylinder by means of a very small communicating passage, but it may be placed in free communication with the supply tank by opening a small mushroom type valve which is seated in the piston of the exhaust valve head. An actuating spindle passes down the centre of the exhaust valve stem and it is so arranged in association with the control valve that it lifts the small mushroom type valve off its seat when the control valve spindle is moved to the "return" position, and it permits the small mushroom valve to close when the control valve spindle is moved to the "neutral" position.

In order that the invention may be clearly understood and carried into effect two embodiments of the same will now be described by aid of the accompanying drawings in which Fig. 1 is a somewhat diagrammatic view in section of the complete valve according to one embodiment and Fig. 2 is a view of a detail to an enlarged scale showing a further embodiment in which the automatic operation of the exhaust valve according to the first embodiment is supplanted by mechanical operation.

The valve illustrated in the drawings is for the purpose of controlling the return stroke of the one or more rams of an upwardly acting hydraulic press and for this purpose it is used in conjunction with an automatic admission valve and a spring loaded decompression or relief valve, neither of which valves are illustrated in the drawings.

The valve of the present invention, according to one embodiment illustrated, has in combination a control valve, a prefilling valve, and an exhaust valve.

Referring to the drawing, the control valve consists of a plunger 1 working in a cylinder 2 within which it is reciprocable by operation of a hand lever 3. The valve plunger 1 has two full diameter portions separated by a portion 4 of reduced diameter and within the cylinder 2 are cut two annular grooves 5 and 6 that are separated by an annular ring 7 having an integral diameter nearly the same as the full external diameter of the plunger so that one is a working fit within the other.

The annular groove 5 receives pressure liquid from a pump or accumulator through a connection 8, said pump also being connected to the approach cylinders of the press.

The main casing of the combined valve of the present embodiment consists of two pipe sections 9 and 10 which are bolted together so as to grip between them an annular member 11 forming on one side a seat for the prefilling valve and having on the opposite side a spider for supporting a guide bush for the spindle of the exhaust valve.

The cylinder 2 of the control valve plunger 1 is mounted on a hollow support 12 branching from the pipe section 9 which is curved and terminates in a flange 13 for connecting the section to a pump reservoir or prefill tank not shown. The opposite end of the other pipe section 10 terminates in a flange 14, but in this case such flange is for connecting this pipe section to the one or more press cylinders, also not shown.

As it is desired that liquid from the pump or accumulator entering through the connection 8 shall be free to flow into the upper pipe section 9 in two positions of the operating lever 3, the annular groove 6 is rendered permanently open to the interior of said pipe section 9 by means of a series of holes or channels 15.

Liquid entering into the annular groove 5 is free to pass to the other annular groove 6, and so into the pipe section 9, by reason of the reduced portion 4 of the control valve plunger 1 bridging, in these two positions of the operating lever, the two annular grooves 5 and 6.

By pulling the lever 3 to the left in the drawing, the

control valve plunger 1 is pulled upwards thus moving the lower full diameter portion into the section of the cylinder bore constituted by the annular ring 7. The annular groove 5 is thus isolated from the annular groove 6 and in consequence the pressure liquid from the pump or accumulator is forced to flow to the approach rams of the hydraulic press and, upon actuation of the automatic admission valve, also to the one or more main rams of the press through an opening 8^a in the lower pipe section 10.

The prefilling and exhaust valves according to the construction illustrated are in axial alignment with the control valve and consist, in the case of the prefilling valve, of a valve member 16 which is supported by a spring 17 acting on a plunger 18, with the upper chamfered edge of the member in engagement with a seating 19 on the underside of the annular member 11, and in the case of the exhaust valve, of a piston-like member 20 working in a cylinder 21 within the interior of the prefilling valve member 16.

The upper edge of the exhaust valve member 20 is chamfered and seats against a seating constituting the chamfered lower edge of an opening 22 communicating with the interior of the upper pipe section 9. With the exhaust valve member 20 in the open position liquid from the press is permitted to pass from the lower pipe section 10 to the upper pipe section 9 by way of radial passages 23 in the prefill valve member 16 and opening 22.

The exhaust valve member 20 is held in the raised or closed position by a spring 24 acting against an enlarged head 25 on the upper end of a stem 26 attached to or forming an integral part of the exhaust valve member.

With the exhaust valve in the closed position there is provided beneath the member 20 a space 27 which is in open communication with the interior of the lower pipe section 10 by way of a small hole 28. By suitably reducing the upper end of the exhaust valve member there is provided an annular surface 29 against which the pressure liquid from the interior of the lower pipe section, entering through the passages 23, can act in opposition to the pressure within the space 27. Both ends of the exhaust valve member, therefore, are under the influence of the pressure in the press cylinder and normally the member is held closed against its seating by the spring 24 and the superior pressure on its lower end.

To destroy this balance and permit the exhaust valve to be forced away from its seating it is necessary that means be provided whereby the space 27 is opened to exhaust. In the example illustrated such means takes the form of a small mushroom valve 30 which is held against its seat by a spring 31 and is adapted to be forced off its seat by the plunger 1 of the control valve in its downward movement through the intermediary of a spindle 32 forming an extension of the plunger 1 to which it is connected by adjusting means 33 which permit the effective length of the spindle 32 in relation to the valve 30 to be suitably varied.

The valve 30 has a stem 34 which is a sliding fit in a bore in the body of the exhaust valve 20 and this bore forms a continuation of a bore extending up the stem 26 of the exhaust valve in which fits slidably, the lower end of the spindle 32.

The stem 34 of the valve 30 has an axial passage 35 at its centre which is closed at the valve head end and open at its upper end. This upper end is reduced in diameter and the thin wall thus formed is pierced by radial slots 36. Similarly radial holes 37 pierce the wall of the stem at its lower end just above the head of the valve 30 and these latter holes form a communication between the lower end of the axial passage 35 and a circumferential groove 38 formed by suitably reducing the diameter of the surrounding portion of the stem 34.

When the valve 30 is forced downwards off its seat the groove 38 is rendered open to the space 27 beneath the exhaust valve 20. Liquid within this space is thus

permitted to flow into the axial passage 35 and out through the radial slots 36. As the upper open end of the passage 35 is closed by the contacting end of the spindle 32, lateral passages 39 are provided in the wall of the stem 5 26 through which the liquid flowing from the space 27 can escape into the interior of the upper pipe section 9.

The above construction is best seen upon reference to Fig. 2 illustrating an embodiment in which the exhaust valve member 20 is of the same diameter throughout its length.

Now let us consider the employment of a control valve such as described above for operating an upwardly acting hydraulic press having a press ram and two approach rams and actuated by pressure liquid supplied by a hydraulic pump. The manually operated control valve is so arranged and connected that when the control valve spindle is in the "neutral" and "return" positions the liquid from the pump and from the approach cylinders is freely bypassed back to the pump supply tank; and, when the control valve spindle is in the "pressing" position, raised position in Fig. 1, the pressure liquid from the pump is directed to the approach cylinders. Thus, when the control valve spindle is moved upwardly to the "pressing" position the approach rams lift the 15 press table and associated press ram up to the work and during this approach stroke the press cylinder is so connected that it is filled with liquid from the pump supply tank passing through the prefill valve which is opened against the spring 18 by the difference of pressure or 20 head of liquid. When the press table meets the work the automatic admission valve, actuated by the pressure in the approach cylinders, directs pressure liquid from the pump through passage 8^a to the press cylinder in addition to the approach cylinders; the prefilling valve is 25 closed as the pressure builds up in the press cylinder, and therefore in pipe section 10, and the pressing operation is performed. When the control valve spindle is moved to the "neutral" position shown in Fig. 1, liquid from the approach cylinders is bypassed through the 30 control valve by way of passage 8 to exhaust and the pump is bypassed; liquid is locked in the press cylinder by the prefill valve which is closed, but pressure in the press cylinder is allowed to fall gradually by the aforesaid spring loaded decompression valve, or throttling 35 valve which is interposed between the press cylinder and the pipe line, between the approach cylinders and the control valves, which is now connected to exhaust. The said decompression valve is so arranged that the flow is in one direction only, away from the press cylinder, and so adjusted that the pressure falls to a figure such that it is just sufficient to support the weight of the press table and moving parts. This decompression valve may 40 be described very briefly as a relief valve which is so constructed that the spring load and the valve lift or opening are independently adjustable; the spring load being adjusted so that the ultimate pressure at which the valve closes is sufficient to support the weight of the moving parts; and as the valve lift or opening determines the rate of decompression, the latter is adjusted to give the desired rate. When the control valve spindle is moved 45 downwardly to the "return" position, the small mushroom valve 30 is actuated by the control valve spindle so as to place the space 27 beneath the piston of the exhaust valve in communication with the supply tank and this permits the exhaust valve to be opened by the pressure in the press cylinder acting on the annulus 29 of the exhaust valve piston. With the exhaust valve open, the press cylinder is now in communication with the supply tank and the press table is free to fall by gravity, 50 liquid from the press cylinder passing through the exhaust valve 20, and liquid from the approach cylinders passing through the control valve by way of passage 8 to exhaust.

The embodiment illustrated in Fig. 2 differs in function 55 from that illustrated in Fig. 1 in that the orifice con-

trolled by the small valve 30 is made very large in comparison with the hole 28 so that when the valve 30 is opened the space 27 will be wholly exhausted thus allowing the exhaust valve 20 to be pushed from its closed position to the open position by contact between the adjusting means 33 and the upper enlarged end of the stem 26 of the exhaust valve.

In the above embodiments the control valve is described as being manually operated; nevertheless the control valve may be remotely controlled or pilot-operated without departing from this invention. It will be further understood that the combined prefilling and exhaust valve may be mounted on a common manifold to supply a number of press cylinders having associated press rams which act in unison in association with a common press table. Furthermore, if increased pumping capacity is required, more than one pump may be employed.

We claim:

1. A combined control, prefill, and exhaust valve for hydraulic presses comprising, in combination, a hollow casing having a pressure fluid inlet at one end and a pressure fluid outlet at the other end, a control valve supported on said casing having connections with a source of pressure fluid and with the inlet end of the casing, said control valve having a shiftable member operative in one position to block fluid flow from said source and in another position to direct fluid flow into said casing, a prefill valve member mounted within said casing so as to control communication between the two ends thereof and having opposite ends respectively subjected to the pressure of the fluid in the inlet and outlet ends of the casing, yieldable loading means normally operative to hold said valve member in a closed position in which it is effective to interrupt communication between the ends of the casing, said loading means permitting said valve member to move to an open position under the influence of the pressure in the inlet end of the casing upon a predetermined decrease in the pressure in the outlet end of the casing, a passage in said valve member affording communication between the ends of the casing when said valve member is in closed position, an exhaust valve normally positioned to close said passage, and means interposed between the shiftable member of said control valve and said exhaust valve for moving the latter to open position upon a shift of the control valve member to said other position.

2. A combined control, prefill and exhaust valve as defined in claim 1, in which said exhaust valve is in the form of a piston having differential areas exposed respectively to the pressure in the inlet and outlet ends of the valve casing when the prefill valve member is in closed position, and a relief valve operable to reduce the pressure on one end of the piston to permit its movement to open position by the pressure exerted on its other end.

3. A combined control, prefill and exhaust valve as defined in claim 1, in which said exhaust valve is in the form of a piston having opposite ends exposed respectively to the pressure within the inlet and outlet ends of the casing, and a relief valve connected so as to reduce the differential between the pressures on the ends of the piston when opened and thereby condition said exhaust valve for movement to open position mechanically as an incident to the actuation of the control valve.

4. A control valve for hydraulic presses comprising, in combination, a hollow casing having a pressure fluid inlet at one end and a pressure fluid outlet at the other end, a control valve having connections with a source of pressure fluid and with the inlet end of the casing, said control valve having a shiftable member operative in one position to block fluid flow from said source and in another position to direct fluid flow into said casing, a prefill valve member seated within said casing so positioned that the upper area of said prefill valve member is exposed to the pressure in the inlet end of the casing and the lower area of the valve member is exposed to the pressure in the outlet end of the casing, yieldable means loading said prefill valve member into closed position with such force as to be overcome by a predetermined reduction in the pressure differential between the ends of the casing allowing fluid from the inlet end to bypass said prefill valve member and flow through said outlet, and exhaust valve positioned within said prefill valve member, a passage connecting the outlet end portion of said casing to the inlet end portion of said casing which is closed by moving said exhaust valve, a spindle forming an extension of the control valve member engageable with said exhaust valve for positively opening the exhaust valve in response to a predetermined movement of the control valve member thereby allowing fluid to exhaust from the outlet end of the casing through the inlet thereof.

5. A control valve for hydraulic presses comprising, in combination, a hollow casing having a pressure fluid inlet at one end and a pressure fluid outlet at the other end, a control valve having connections with a source of pressure fluid and with the inlet end of the casing, said control valve having a shiftable member operative in one position to block fluid flow from said source and in another position to direct fluid flow into said casing, a prefill valve member seated within said casing and normally interrupting fluid flow between the inlet and outlet of the casing, yieldable means urging said prefill valve member into seated relationship with said casing, an exhaust valve slideable within said prefill valve member, a chamber above said exhaust valve, a portion of the base of which is an area or the top of said exhaust valve, an exhaust passageway interrupted by said exhaust valve, a relief valve within said exhaust valve, a relief passageway associated with said relief valve, and means operable by said control valve member to shift said relief valve thereby allowing fluid to flow from the outlet end of the casing through the relief passageway into said exhaust valve chamber, thereby reducing the differential pressure on said exhaust valve to facilitate its opening against the yieldable means which normally retains it in its seated position.
